STEAMING TUBE FOR HAIR WAVING.

Application filed February 20, 1926. Serial No. 89,777.

Our invention relates to tubular containers for enclosing strands of hair which have been prepared for a waving process, during that part of the process wherein the strands of hair are heated.

One of the objects of our invention is to accomplish the application of heat to the strands of hair sought to be waved, in a highly efficacious manner, for the purpose intended.

Another object of our invention is to accomplish the heating of the strand of hair sought to be waved by means of a permanent waving process in an enclosure, to restrict the escaping of vapors from the vicinity of the hair strand and to directively vent the escaping vapors in a highly efficacious manner.

Another object of our invention is to accomplish the heating operation of a permanent waving process in a highly efficient manner, at the same time preventing the charring or discoloration of any portion of the exterior of the container enclosing the strand of hair during such a heating operation, substantially until the heating operation has reached that point wherein it should properly be discontinued or reduced in intensity of heating.

Another object of our invention is to accomplish a visible indication effective only upon substantially reaching that part of the heating operation wherein the heating should be discontinued or reduced.

Another object of our invention resides in the provision of an improved process of accomplishing the treatment and heating of a strand of hair during a waving process, whereby effective and superior results may be secured.

The above and other objects of our invention will appear from the following description, in which description a container, which is a specific embodiment of our invention, is described, reference being had in this description to the drawings illustrating the said embodiment and forming portions of this specification.

In the accompanying drawings, Fig. 1 shows, mostly in enlarged section, a hair waving apparatus, comprising a container capable of being utilized in the practice of our invention and embodying the principles thereof;

Fig. 2 illustrates, in an enlarged view, an intermediate step in the formation of the

tubular container comprised in the showing of Fig. 1;

Fig. 3 shows an elevation of the tubular container of Fig. 1, shown in a normal size, completed and ready for use in the waving process;

Fig. 4 is an enlarged section taken on the line 4—4 of Fig. 3;

Fig. 5 is a view of the container in place and enclosing a strand of hair to be heated during the waving process and prior to the application of the heating tube, as illustrated in Fig. 1;

Fig. 6 is an enlarged perspective view of another embodiment of our invention;

Fig. 7 is an enlarged perspective view of another embodiment of our invention which comprises an inner wall of aluminum foil and an outer wall of paper;

Fig. 8 is a sectional view, similar to that taken on the line 4—4 of Fig. 3, of another embodiment of our invention, a side elevation of which would appear as does Fig. 3; and

Fig. 9 illustrates a fragmentary enlarged view of another embodiment of our invention.

Referring first to Figs. 1 to 5, inclusive, in which figures is illustrated one embodiment of our invention, and in all of which figures like parts are designated by like reference characters, the tubular container embodied in these figures of drawing comprises a rolled tube comprising an inner layer 1 and an outer layer 2, both of paper, with an intermediate layer 3, preferably of aluminum foil or like form-sustaining, pliable heat conducting material. Although the thickness of paper and foil may vary, we preferably employ paper, forming the interior and exterior walls of the tubular container, relatively very thin as compared with the relatively thick paper and pasteboard tubular walls of containers previously in use so far as we are aware. The paper may therefore be made very thin and may be of rice paper only a few thousandths of an inch in thickness, being preferably of a thickness not exceeding that of .015" and being preferably much less than this, such as from .005" to .0075".

The foil may vary in thickness, foil of a thickness of .0015" wall having been found satisfactory, but preferably the foil will be between .001" and .005" in thickness and may comprise superposed foil layers, or may be preferably of but a single layer of foil

except for overlapping at the joints, making a convenient method of closing the seam.

Having set forth herein the dimensions preferably imposed upon the thickness of the constituent portions of the walls of our improved tube, we wish it to be understood that the drawings are therefore to be taken as illustrative of the form of tube and the relative positioning of the parts, rather than to represent, according to scale, the thicknesses of the constituent paper and foil layers thereof.

The tubular container of Figs. 1 to 5, inclusive, and of Fig. 8, is preferably formed as illustrated in Fig. 2, by the rolling together of a sheet of foil 3 and a sheet of paper 4 until the roll contains the desired number of layers of superposed foil and paper, and then securing, in any desired way, the exterior end of the roll, such as by applying an adhesive to the inner face of the outer edge portion to cause it to adhere to the underlying layer of rolled material substantially as illustrated in Figs. 4 and 8. In the embodiments of our invention illustrated in Figs. 6 and 7, however, we show tubular containers, in which the inner tube 5 is of foil, as above described, and the outer layer is shown as a narrow band at 6, Fig. 6, and as a sheet 7, Fig. 7, of a width somewhat less than the width of the foil 5. In the figures, the inner layer of foil has its edges secured together in any desired manner and the outer layer of paper is applied to the exterior of the first formed tube of foil in a manner easily understood by reference to the drawings referred to, the ends of the paper being secured together by adhesive or the like. Fig. 8 shows a tube wherein we increase the number of foil and paper layers.

In practice, we may substitute for the outer layer of paper, in any of the embodiments herein illustrated and described, an outer layer of any material discolorable at a critical temperature, and may apply it in other forms than as a sheet. For instance, as illustrated in Fig. 9, we show a portion of a tube in perspective, having a wrapping 8 of a textile material, such as cotton thread, which is discolorable under the influence of heat.

In Fig. 6, we show a modification of our invention, wherein we dispense with the outer enclosing paper tube and employ instead a tube of metallic foil shown at 3, and on the outer surface thereof, preferably at that portion of the tube which in practice is most remote from the scalp of the patient, we place a piece of paper, preferably in the form of a band, as shown at 4, which may be secured in place by means of adhesive, or in any other convenient manner, but which will adhere closely to the metallic tube 3 and be responsive at all times to the thermal condition thereof. The tube of Fig. 9

employs a winding of thread for such paper band.

The tubes of our invention are preferably pierced after forming, as shown at 9, the opening thereby provided through the wall, 70 being preferably disposed adjacent an end portion of the tube. The projecting end portions of the tube are preferably of foil or like pliable material, capable of being annularly compressed, or crimped, as shown 75 in Figs. 1 and 3, at 35 and 36, and as indicated by dotted lines in Fig. 3.

The waving operation may be performed variably, but to convey a better understanding of our invention, we will describe a typical waving operation in which our invention may be advantageously practiced.

At 10, we show a human scalp from which a strand of hair 11 is gathered preparatory to waving. The strand is first connected 85 with a curler rod 12, adjacent the scalp, by a string 13, which engages in the notch 14 in the end of the rod, and is then wound around the rod and tied thereto at a point removed from the string 13. The hair so wrapped is then stretched lengthwise around the rod. The hair is treated with a suitable softening solution, usually containing an alkali and oil, prior to the stretching operation. A strip of absorbent material 16 is 90 next wrapped around the strand of hair wound on the rod, and is secured at each end so that it encloses the same. Such strip, or pad, is usually treated with the same solution with which the hair was first moistened, and is usually moistened prior to its application.

A felt washer 17 having a slit therein leading to a central aperture 37 is applied to the strand next to the scalp. The container is then placed around the portion of the strand which is secured upon the rod and enclosed by the pad. The foil end portions of the container extending beyond the ends of the paper, will be sealed to maintain its tubular form by means of a gummed portion on the paper, as indicated at 21. The metal jacket thus formed contributes toward more equal distribution of the heat to the hair within the tube during the heating operation, so that the entire length of strand wound on the rod will receive more nearly the same degree of heat and thus prevent undesirable action on the hair which would otherwise be caused by uneven heat distribution.

The operator places the tube around the strand, preferably with one end of the projecting foil against the washer 18 and with a suitable tool, or with the fingers, crimps the foil ends against the strand, as shown at 15, where it will remain due to its inherent non-resiliency, thus sealing the end of the tube around the strand so that the solution and steam cannot pass to the scalp during the heating operation. The other 125

end of the projecting foil can be crimped in the same manner around the strand to seal the upper end of the tube. It will be observed that with this means of sealing and securing the tube in position, little time has to be consumed by the operator in applying and removing the tube, thereby eliminating much of the time now required to apply and remove clamp devices usually employed for this purpose.

10 A preferably two part fibrous washer 18, the portions of which are riveted together at 38, of heat resisting material having a centrally disposed pair of semi-circular jaws, 15 is then applied around the strand of hair so that it lies adjacent the felt washer. The two parts are swung on the rivet 38 to bring the jaws against the crimped portion 35 of the inner foil end of the container. The 20 strand of hair extends through the central apertures in the washers, the felt serving as a buffer for the scalp, and the fibrous washer serving as a bearing for the heater, to prevent the heat from reaching the scalp and to 25 assist in preventing forcible displacement of the crimped foil portions.

It is customary to wait for the hair to grow to a length at which the wave is entirely out of the hair before attempting to 30 put in another wave. With this form of tube, the hair can be waved at any length regardless of the distance the wave in the hair has grown from the scalp, as the tube can be crimped at any point of its length to enclose 35 and seal the hair intermediate the scalp and the old wave. When the tube is crimped in such relation on the strand, there can be no passage of steam, hot gases or solution to the waved portion of the hair, so that the 40 wave already therein will not be harmed while forming the new wave. It will also be observed that the tube can be crimped and sealed within the fiber washer, so that the curls can be started close to the scalp.

45 When the tube has been positioned around the strand of hair enclosed by the pad as above described, an electric heater 22 is placed around the tube with one end thereof bearing against the fibrous washer 18. The 50 tube is provided with one or more apertures 9, close to the end thereof which lies adjacent the scalp, to permit the gases and steam to escape. The natural tendency of the 55 heat and hot gases is to seek the uppermost portion of the tube, and it is customary to permit the same to escape through the upper portion of the tubes. With our tube acting as does an oven, due to the escape at the bottom of the tube, the hair is subjected to a 60 uniform heat and therefore will form a more uniform wave, for after the current has been turned on, the vapors can escape and pass to atmosphere through the apertures 9 through the walls of the tube.

65 After the solution within the tube reaches

a predetermined condition of dryness, the paper on the exterior wall of the tube will start to become browned prior to the reaching of a temperature within the tube at which the hair will burn or become brittle; 70 thus, browning of the tube will indicate the proper time to remove the heater. This indicating is accomplished by virtue of the thermal characteristics of the tube, since, as made, it presents very little resistance to the 75 free passage of heat through its walls, and therefore, heat will be conducted freely from the interior wall of the tubular heater through the tubular walls of the container, and the moisture enclosed with the hair in 80 the oven-like container will, until it is exhausted by being vaporized, effect a certain cooling of the space within the tubular container comprising the foil and paper portions. In the embodiments illustrated, this 85 cooling temperature existing at the interior surfaces of the walls of the container tube, will effect a cooling, so long as moisture is present within the tube, through the walls to their exterior surfaces. Due to this cooling, the exterior surface of the tube will not be unduly hot for handling purposes. Due to the relatively efficient thermal conductivity of heat through the walls of the tube, the 90 temperatures on its interior and exterior surfaces will be substantially the same at all times, and therefore, charring of the exterior surfaces of the tube, which is common in tubes of the prior art with which we are familiar and which comprise relatively thick 95 pasteboard walls or the like, prior to the achievement of a temperature within the tube which would effect charring of paper, is effectively prevented.

The waving operation is therefore attended, until it is practically completed, with none of the smoke of charring pasteboard, or the like, which is unpleasant to the patient being operated upon and to the operator, and moreover, when final discoloration of the exterior surfaces, which 105 preferably comprise paper in the embodiments illustrated, does occur, it is an indication to the operator that the heating operation is substantially completed and that the 110 operator therefore should be attentive to the matter of discontinuing the heat.

This is a great advantage in waving processes which heretofore have been carried on practically entirely by timing the heating 115 operation without adequate variation in the time of heating to allow for the different amounts of moisture contained within the tubes, together with the strands of hair to be treated, and to allow for the varying heat 120 conditions prevalent within the tubular containers under different conditions of use, and consequent sometimes upon the varying 125 strength of electrical current, the varying thermal properties of the tubes used, and 130

the varying compositions of hair treating lotions applied to the hair during or prior to the heating process.

By employing this principle in any waving process, the condition of the tube will serve as an indicator to the operator to show when the strand of hair has been sufficiently heated to complete the waving process, and such condition can be observed at all 10 times without disturbing or removing any part of the apparatus.

In Fig. 6, we have illustrated a modified form of container which is formed substantially entirely of metal foil 30. This container is formed of a sheet of foil and is rolled in tubular form and secured bylapping one of the edges over the other edge and pressing them securely together. The 15 apertures 9 are provided in this tube for the same purpose above specified, and the tube is applied in the same manner to a strand of hair and for the same purpose as above set forth. Various materials could be used to form the tube, to serve all purposes of our 20 invention, so long as they were pliable and of a nature to provide a self-retaining seal when crimped around a strand of hair, and also capable of conducting heat at the temperature demanded without fusing. In Fig. 25 30, a band of rice paper adapted to discolor under a critical heat, is shown as applied to the end portion of the tube adhering to its exterior wall and secured in place by overlapping adhering gummed edge portions.

35 In Fig. 7, we show a container tube comprising an outer layer of paper with an inside layer of foil. In all of the embodiments illustrated, the wall thicknesses of foil and paper may be varied, but excellent results 40 may be obtained when the dimensions hereinabove set forth are employed where such materials specified enter into the composition of the tubular containers.

Various changes can be made in the materials and details used for forming containers without departing from the spirit of our invention and the scope of what we claim.

1. A container for enclosing a strand of hair during a waving process, consisting of a 50 tube having a substantially solid pliable wall comprising metallic foil, said wall being an efficient conductor of heat from its exterior to its interior surface.

2. A container for enclosing a strand of hair during the heating operation of a waving process, comprising a tube having wall portions of so little resistance to the flow of heat therethrough that when exteriorly heated the temperature on the interior and exterior surfaces of the tube will be maintained substantially equal, and thermo-responsive indicating means visible from the tube exterior to indicate a critical temperature in the waving process heating of the hair.

3. A container for enclosing a strand of

hair during a waving process, consisting of a sheet of paper and a sheet of pliable metallic foil, said sheets being formed as a tube with an inner and/or an outer surface of paper, the successive layers of foil and paper being joined intimately together to exclude air between the sheets.

4. A container for enclosing a prepared strand of hair during the heating operation of a waving process, comprising a tube placed over the strand, and thermo-responsive means for visibly indicating from the exterior of the tube substantially the temperature within the tube at a critical point in the heating operation.

5. A container for enclosing a strand of hair during the heating operation of a waving process, comprising a tube having wall portions of so little resistance to the flow of heat therethrough that when exteriorly heated the temperature on the interior and exterior surfaces of the tube will be maintained substantially equal, and thermo-responsive indicating means comprising a relatively thin sheet of material discolorable under the influence of a critical temperature and visible from the tube exterior to indicate a critical temperature in the waving process heating of the hair.

6. A container for enclosing a prepared strand of hair during the heating operation of a waving process, comprising a tube placed over the strand, and thermo-responsive means comprising a relatively thin sheet of material discolorable under the influence of a critical temperature, for visibly indicating from the exterior of the tube substantially the temperature within the tube at a critical point in the heating operation.

7. A container for enclosing a prepared strand of hair adapted to be steamed during the heating operation of a waving process, comprising a metallic tube placed over the strand, said tube having substantially confining end walls, and a piece of material discolorable under the influence of a critical temperature affixed to the exterior surface of the tube.

8. A container for enclosing a prepared strand of hair adapted to be steamed during the heating operation of a waving process, comprising a metallic tube placed over the strand, said tube having substantially confining end walls, and a piece of material discolorable under the influence of a critical temperature affixed to the exterior surface of the tube, adjacent the end of the tube, remote from the scalp of the patient.

9. A container for enclosing a prepared strand of hair adapted to be steamed during the heating operation of a waving process, comprising a metallic tube placed over the strand, said tube having substantially confining end walls, and a piece of relatively thin paper material discolorable under the

- influence of a critical temperature affixed to the exterior surface of the tube, adjacent the end of the tube, remote from the scalp of the patient.
- 6 10. A container for enclosing a prepared strand of hair adapted to be steamed during the heating operation of a waving process, comprising a metallic tube placed over the strand, said tube having substantially confining end walls, and a band of paper material discolorable under the influence of a critical temperature affixed to the exterior surface of the tube, adjacent the end of the tube, remote from the scalp of the patient.
- 10 11. A container for enclosing a strand of hair during a waving process, consisting of a sheet of paper, and a sheet of metallic foil, said sheets being formed as a tube with an inner and an outer surface of paper.
- 15 12. A container for enclosing a strand of hair during the heating operation of a waving process, consisting of a sheet of paper, and a sheet of foil of greater width than the paper, said paper and foil being secured together as a tube with the paper forming the inner and outer surface thereof.
- 20 13. A container for enclosing a strand of hair during the application of heat in a waving process, consisting of an interior and an exterior wall of paper, and metallic foil intermediate said walls of paper.
- 25 14. A container for enclosing a strand of hair during the heating of a waving process, consisting of an interior and an exterior wall of paper, and a sheet of aluminum foil intermediate said walls of paper.
- 30 15. A container for enclosing a strand of hair during the heating operation of a waving operation, consisting of a paper tube, and pliable metal material extending from one end of said tube adapted to be inwardly crimped to substantially seal the tube adjacent an end thereof.
- 35 16. A container for enclosing a strand of hair during the heating operation of a waving process, consisting of a plurality of sheets rolled in tubular form, one of said sheets being formed of soft pliable metal.
- 40 17. A container for enclosing a strand of hair during the heating operation of a waving process, consisting of a tube formed of sheet paper and a sheet of soft pliable metal.
- 45 18. A container for enclosing a strand of hair during the application of heat in a waving process, consisting of a paper tube, and pliable metal projecting from the ends of said tube, said metal being adapted to be annularly crimped inwardly to substantially seal the tube.
- 50 19. A container for enclosing a strand of hair during the heating operation of a waving process, consisting of a paper tube, and a sheet of aluminum foil of greater width than said paper, said sheets being formed in a tube with the ends of said foil project-
- ing beyond the ends of said paper and with the paper forming the interior and the exterior walls thereof, the projecting ends of said foil being adapted to be annularly crimped inwardly to substantially seal the ends of the tube.
- 55 20. A container for enclosing a strand of hair treated with a solution to be steamed therein during the application of heat, consisting of a tube formed of sheets of paper and foil, said tube having an aperture in the wall thereof adjacent one end to permit the escape of steam and gases when heat is applied, said tube when applied to the strand of hair being arranged with the apertured end adjacent the scalp.
- 60 21. A container for enclosing a strand of hair during the heating operation of a waving process, consisting of a sheet of paper and a sheet of pliable metal rolled together in tubular form, said tube sealing a desired length of hair therein by being crimped transversely of its length.
- 65 22. A container for enclosing a strand of hair during a heating operation of a waving process, consisting of a tube formed of paper and pliable metal.
- 70 23. A container constructed of sheet metallic foil for enclosing a strand of hair during the application of heat in a waving process, said foil effecting a substantial seal when pressed annularly inwardly.
- 75 24. A container constructed of sheet aluminum foil, or like material for enclosing a strand of hair during the application of heat in a permanent waving process, said foil adapted to be deformed by an inward annular crimping to effect a substantial seal of the container, the deformed foil being substantially self form-sustaining.
- 80 25. A container constructed of a sheet of pliable metallic foil rolled in tubular form for enclosing a strand of hair during the application of heat in a permanent waving process, said foil adapted to be deformed by inwardly compressing the foil to effect a substantial seal of the formed tube against the free passage of vapors.
- 85 26. A container constructed of material containing metal which will readily conduct heat applied to permanently wave hair without fusing of the material and capable of providing a substantial seal to restrict the flow of vapors therefrom when deformed by compression, said material being sufficiently pliable as to remain substantially in the deformed sealing condition after the compressive force is relieved.
- 90 27. A container for enclosing a strand of hair during a waving process, substantially solid tubular lateral walls for said container, comprising substantially resilient material whereby it can be sealed against the strands of the hair merely by crimping.
- 95 28. A container for enclosing a strand of hair during a waving process, substantially solid tubular lateral walls for said container, comprising substantially resilient material whereby it can be sealed against the strands of the hair merely by crimping.

- hair during the heating operation of a waving process, comprising a tube having a longitudinal passage substantially closed at its top and containing the strand of hair, and having an opening at the bottom of such passage for relatively more ready conduction of vapors created in the passage, therefrom.
29. A container for enclosing a strand of hair during the heating operation of a waving process, comprising a strand embracing portion adapted to be annularly compressed, said portion comprising material of such a nature as to take a "set" after such compression, to effect substantial sealing of the container between the strand and the said embracing portion of the container.
30. A tubular container for enclosing a strand of hair during the heating operation of a waving process, adapted to conduct heat applied to its exterior surface through its walls to communicate such heat to the strand of hair enclosed by the tube, the tube walls having a thermal conductivity, such that its exterior surface will have substantially the same temperature as its interior surface.
31. A tubular container for enclosing a strand of hair during the heating operation of a waving process, adapted to conduct heat applied to its exterior surface through its walls to communicate such heat to the strand of hair enclosed by the tube, the tube walls having a thermal conductivity, such that its exterior surface will have substantially the same temperature that exists within the tube, and means discolorable by the effect of heat visible from the exterior of the tube to indicate a critical temperature within the tube.
32. A container for enclosing a strand of hair during the heating operation of a waving process, and adapted to communicate extraneously applied heat through its walls to the strand of hair operated upon, comprising a sheet of metallic material.
33. A container for enclosing a strand of hair during the heating operation of a waving process, and adapted to communicate extraneously applied heat through its walls to the strand of hair operated upon, comprising a sheet of pliable metallic material.
34. A container for enclosing a strand of hair treated with a solution to be steamed therein during the application of heat, consisting of a tube having an aperture in the wall thereof adjacent one end to permit the escape of steam and gases when heat is applied, said tube when applied to the strand of hair being arranged with the apertured end adjacent the scalp.
35. A container for enclosing a strand of hair treated with a solution to be steamed therein during the application of heat, consisting of a tube having an aperture in the wall thereof adjacent one end to permit the escape of steam and gases when heat is applied, said tube when applied to the strand of hair being arranged with the apertured end adjacent the scalp, said tube having walls sufficiently thermal conducting as to efficiently conduct heat applied extraneously of the tube walls through its walls to the interior of the tube.
36. The method of processing a treated wound strand of hair comprising confining the prepared strand with moisture within a metallic wrapper and heating the confined hair and moisture by heat applied to the wrapper extraneously thereof.
37. A wrapper for enclosing a prepared strand of hair, together with moisture, during the heating operation of a waving process, comprising a sheet of metal foil.
38. A container for a wound strand of hair during the process of "permanent waving" of the strand, metallic tubular walls therefor of a length at least four times their diameter and of a weight not in excess of one-fifth of an ounce.
39. A tubular container for a wound strand of hair during the process of "permanent waving" of the strand, comprising a tubular envelope of metal of a length approximately five and one-half times its diameter and weighing approximately one-tenth of an ounce.
- In testimony whereof we hereunto affix our signatures this 15th day of February, 1926.

CERTIFICATE OF CORRECTION.

Patent No. 1,611,466,

granted December 21, 1926.

to WILBUR S. LEWIS ET AL.

It is hereby certified that error appears in the printed specification of the above mentioned patent requiring correction as follows: Page 5, line 127, claim 27, for the word "resilient" read "non-resilient"; and that the said Letters Patent should be read with this correction therein that the same may conform to the record of the case in the Patent Office.

Signed and sealed this 22nd day of February, A. D. 1927.

DISCLAIMER.

1,611,466.—*Wilbur S. Lewis*, Cleveland, and *John C. Murray*, Lakewood, Ohio.
 STEAMING TUBE FOR HAIR WAVING. Patent dated December 21, 1926. Disclaimer filed July 27, 1929, by the assignee, *The Nestle Lemur Company*.

Specifically disclaims those parts of the said specification and claims which are in the following words, reference being made to page and line numbers of the patent as printed, to wit:

The following words on page 1 beginning on line 22 and ending on line 34: “at the same time preventing the charring or discoloration of any portion of the exterior of the container enclosing the strand of hair during such a heating operation, substantially until the heating operation has reached that point wherein it should properly be discontinued or reduced in intensity of heating.”

“Another object of our invention is to accomplish a visible indication effective only upon substantially reaching that part of the heating operation wherein the heating should be discontinued or reduced.”

The words on page 2 in lines 44 and 45: “at a critical temperature.”

The words on page 2 in lines 64 and 65: “and be responsive at all times to the thermal condition thereof.”

The words on page 3 in lines 24, 25, and 26: “and to assist in preventing forcible displacement of the crimped foil portions.”

The words on page 3 in lines 41 to 44, inclusive: “It will also be observed that the tube can be crimped and sealed within the fiber washer, so that the curls can be started close to the scalp.”

The words on page 3 beginning with line 65 and ending in line 85: “After the solution within the tube reaches a predetermined condition of dryness, the paper on the exterior wall of the tube will start to become browned prior to the reaching of a temperature within the tube at which the hair will burn or become brittle; thus, browning of the tube will indicate the proper time to remove the heater. This indicating is accomplished by virtue of the thermal characteristics of the tube, since, as made, it presents very little resistance to the free passage of heat through its walls, and therefore, heat will be conducted freely from the interior wall of the tubular heater through the tubular walls of the container, and the moisture enclosed with the hair in the oven-like container will, until it is exhausted by being vaporized, effect a certain cooling of the space within the tubular container comprising the foil and paper portions.”

The words beginning in line 110 of page 3 and ending in line 11 of page 4 as follows: “and moreover, when final discoloration of the exterior surfaces, which preferably comprise paper in the embodiments illustrated, does occur, it is an indication to the operator that the heating operation is substantially completed and that the operator therefore should be attentive to the matter of discontinuing the heat.”

“This is a great advantage in waving processes which heretofore have been carried on practically entirely by timing the heating operation without adequate variation in the time of heating to allow for the different amounts of moisture contained within the tubes, together with the strands of hair to be treated, and to allow for the varying heat conditions prevalent within the tubular containers under different conditions of use, and consequent sometimes upon the varying strength of electrical current, the varying thermal properties of the tubes used, and the varying compositions of hair treating lotions applied to the hair during or prior to the heating process.”

“By employing this principle in any waving process, the condition of the tube will serve as an indicator to the operator to show when the strand of hair has been sufficiently heated to complete the waving process, and such condition can be observed at all times without disturbing or removing any part of the apparatus.”

The words on page 4 in line 31: “a critical.”

DISCLAIMER.

1,611,466.—*Wilbur S. Lewis*, Cleveland, and *John C. Murray*, Lakewood, Ohio.
STEAMING TUBE FOR HAIR WAVING. Patent dated December 21, 1926. Disclaimer filed July 27, 1929, by the assignee, *The Nestle Lemur Company*.

Specifically disclaims those parts of the said specification and claims which are in the following words, reference being made to page and line numbers of the patent as printed, to wit:

The following words on page 1 beginning on line 22 and ending on line 34: “at the same time preventing the charring or discoloration of any portion of the exterior of the container enclosing the strand of hair during such a heating operation, substantially until the heating operation has reached that point wherein it should properly be discontinued or reduced in intensity of heating.

“Another object of our invention is to accomplish a visible indication effective only upon substantially reaching that part of the heating operation wherein the heating should be discontinued or reduced.”

The words on page 2 in lines 44 and 45: “at a critical temperature.”

The words on page 2 in lines 64 and 65: “and be responsive at all times to the thermal condition thereof.”

The words on page 3 in lines 24, 25, and 26: “and to assist in preventing forcible displacement of the crimped foil portions.”

The words on page 3 in lines 41 to 44, inclusive: “It will also be observed that the tube can be crimped and sealed within the fiber washer, so that the curls can be started close to the scalp.”

The words on page 3 beginning with line 65 and ending in line 85: “After the solution within the tube reaches a predetermined condition of dryness, the paper on the exterior wall of the tube will start to become browned prior to the reaching of a temperature within the tube at which the hair will burn or become brittle; thus, browning of the tube will indicate the proper time to remove the heater. This indicating is accomplished by virtue of the thermal characteristics of the tube, since, as made, it presents very little resistance to the free passage of heat through its walls, and therefore, heat will be conducted freely from the interior wall of the tubular heater through the tubular walls of the container, and the moisture enclosed with the hair in the oven-like container will, until it is exhausted by being vaporized, effect a certain cooling of the space within the tubular container comprising the foil and paper portions.”

The words beginning in line 110 of page 3 and ending in line 11 of page 4 as follows: “and moreover, when final discoloration of the exterior surfaces, which preferably comprise paper in the embodiments illustrated, does occur, it is an indication to the operator that the heating operation is substantially completed and that the operator therefore should be attentive to the matter of discontinuing the heat.

“This is a great advantage in waving processes which heretofore have been carried on practically entirely by timing the heating operation without adequate variation in the time of heating to allow for the different amounts of moisture contained within the tubes, together with the strands of hair to be treated, and to allow for the varying heat conditions prevalent within the tubular containers under different conditions of use, and consequent sometimes upon the varying strength of electrical current, the varying thermal properties of the tubes used, and the varying compositions of hair treating lotions applied to the hair during or prior to the heating process.

“By employing this principle in any waving process, the condition of the tube will serve as an indicator to the operator to show when the strand of hair has been sufficiently heated to complete the waving process, and such condition can be observed at all times without disturbing or removing any part of the apparatus.”

The words on page 4 in line 31: “a critical.”
